UNITED STATES PATENT OFFICE.

ARTHUR C. BARRETT, OF CHICAGO, ILLINOIS.

EXPANSION-BOLT.

1,116,545.

Specification of Letters Patent. Patented Nov. 10, 1914.

Application filed June 15, 1914. Serial No. 845,311.

To all whom it may concern:

Be it known that I, ARTHUR C. BARRETT, a citizen of the United States of America, and a resident of Chicago, in the county of Cook, State of Illinois, have invented certain new and useful Improvements in Expansion-Bolts, of which the following is a specification.

This invention relates more particularly to that type of expansion bolts in which a longitudinally divided two part sleeve is adapted to receive a lag or like screw-bolt, and with which the placing of said screw-bolt is adapted to expand the divided sleeve into holding engagement with the walls of a receiving socket or orifice formed therefor in a wall or the like. And the present improvement has for its main object to provide a simple and efficient structural formation of sections comprising the expanding sleeve, adapted to offer a minimum resistance to the initial driving of the sleeve into place in its receiving socket, and afford a substantial holding engagement of the sleeve in said socket to resist withdrawal or working out.

A further object is to provide a simple and effective formation of the forward end of the expanding sleeve, whereby any lateral play of the forward end of the sleeve in its receiving socket, as well as a rotation of the sleeve, is prevented.

A still further object is to provide a strong and efficient connection between the sections of the expanding sleeve, and by which said sections are held with their internal screw-threads in proper pitch relation during the initial driving operation, as well as in shipment and ordinary handling. All as will hereinafter more fully appear.

In the accompanying drawings: Figure 1, is a sectional elevation illustrating the present expansion bolt, in an expanded condition in a socket orifice formed therefor in a wall or the like. Fig. 2, is a side elevation of the longitudinally divided sleeve of an expansion bolt embodying the present improvements. Fig. 3, is an elevation showing the interior of one of the sections of the sleeve. Fig. 4, is a transverse section on line $x-x$, Fig. 2. Fig. 5, is a similar view on line $x'-x'$, Fig. 2. Fig. 6, is an elevation of the rear and smaller end of the sleeve. Similar reference numerals indicate like parts in the several views.

Referring to the drawings, 2 represents the expansion sleeve split or divided longitudinally throughout its length into two substantially counterpart sections 3 and 4, and formed with a cylindrical tapering bore having an expanded smooth portion 5 at its forward and larger end, and a threaded portion 6 at its rear and smaller end. And such smooth portion 5 of the bore is adapted to receive and accommodate the unthreaded shank portion of an ordinary lag screw or bolt 1, as usual in the present type of expansion bolts, and as illustrated in Fig. 1.

8 are a series of teeth or serrations formed on the exterior of the sleeve sections 3 and 4. In a longitudinal direction said teeth are preferably of the ordinary triangular form shown, while in a transverse direction, said teeth in the present invention will have a semi-circular form at their base or point of connection with the next adjacent tooth, and semi-elliptical at their crowns as shown. With such special transverse formation of the teeth or serrations 8, an elliptical form is imparted to the main body, of the longitudinally divided expansion sleeve 2, which is adapted to provide ample side clearance to the sleeve as the same is driven into the ordinary round orifice or socket that is divided in a wall or the like for the reception of said sleeve. With the described side clearance and the elliptical crowns of the teeth 8, the resistance to the initial driving of the expansion sleeve 2 into place, is confined to the crowns of the teeth or serrations 8 aforesaid, so that but a minimum degree of frictional resistance is met in such driving operation, and in consequence any liability to independent movement of one sleeve section with relation to the other, and the resulting displacement of the pitch relation of the screw-threaded portions 6 of said sections is reduced to a minimum. Accordingly there is much less breaking strain imposed during the driving operation upon the hereinafter described means by which the sleeve sections 3 and 4 are held in proper assembled relation.

9 is a terminal cone at the forward end of the longitudinally divided expansion sleeve 2, and having a slightly larger diameter than the major diameter of the main body of the sleeve at the crowns of its teeth or serrations 8 and adapting the front end of the expansion sleeve to seat itself snugly

110

in the wall socket or orifice made to receive the sleeve, and which socket or orifice as ordinarily drilled is flared more or less at its outer end.

5. 10 are a pair of diametrically disposed ribs or fins formed on the terminal cone 9 aforesaid, and which act to wedge the forward end of the expansion sleeve firmly in the flaring end of the receiving socket or orifice, 10 against a tendency to turn as the lag screw or bolt is screwed into place in said sleeve.

11 are a pair of tangentially disposed holding ears or lugs formed on the terminal cone portion of the sleeve section 4, and 12 15 are a pair of counterpart surface recesses formed in the exterior of the terminal cone portion of the companion sleeve section 3 and separated from the inner bore thereof by bottom webs 13, as shown. With the described 20 construction aforesaid lugs 11 are bent into the aforesaid recesses and against the bottom webs 13 thereof, to effect a yielding attachment between the forward portions of the sleeve sections 3 and 4, and 25 maintain such sleeve sections in proper relation to each other during the operation of applying the present expansion sleeve to a socket orifice formed therefor in a wall or like structure. By the above described 30 formation of the recess 12 and its bottom web 13 in the enlarged forward portion of the sleeve section 3 of the present structure ample depth of the recess 12 is obtained, without any increase in the diameter of the 35 rear and main portion of the structure, wherein a minimum diameter is a desirable commercial feature.

40 The mode of using as well as the general operation of the parts are the same as the ordinary "lag screw expansion bolts" now in general use in the arts, and do not require a detailed description.

Having thus fully described my said invention what I claim as new and desire to 45 secure by Letters Patent, is:—

1. In an expansion bolt, an expansion sleeve comprising two longitudinal sections connected together at their forward ends and formed with a central longitudinal bore 50 which co-operates with a screw-bolt to effect a lateral spreading of the sleeve section, each section having a longitudinally disposed series of teeth on its exterior surface, and each tooth extending transversely 55 the width of the section and formed with a semi-elliptical crown.

2. In an expansion bolt, an expansion sleeve divided longitudinally to form a pair of substantially counterpart sleeve sections 60 having at their forward ends enlarged cone portions, one cone portion having a pair of lateral holding ears and the other cone portion having a corresponding pair of surface recesses and separated from the bore 65 of the expansion sleeve by bottom webs, and

adapted for engagement with said holding ears.

3. In an expansion bolt, an expansion sleeve divided longitudinally to form a pair of substantially counterpart sleeve sections 70 provided on their exterior with teeth or serrations which have a semi-circular form at their bases and a semi-elliptical form at their crowns, the said sleeve sections having at their forward ends terminal cone portions, and means adjacent to said cone portions for securing the sleeve sections together.

4. In an expansion bolt, an expansion sleeve divided longitudinally to form a pair 80 of substantially counterpart sleeve sections provided on their exterior with teeth or serrations which have a semi-circular form at their bases and a semi-elliptical form, at their crowns, the said sleeve sections having 85 at their forward ends terminal cone portions having diametrically disposed fins on their exteriors, and means adjacent to said cone portions for securing the sleeve sections together.

5. In an expansion bolt, an expansion sleeve formed with a screw-thread in the rear portion of its central bore and divided longitudinally to form a pair of substantially counterpart sleeve sections provided 95 on their exteriors with teeth or serrations which have a semi-circular form at their bases and a semi-elliptical form at their crowns.

6. In an expansion bolt, an expansion 100 sleeve formed with a screw-thread in the rear portion of its central bore and divided longitudinally to form a pair of substantially counterpart sleeve sections having at 105 their forward ends enlarged cone portions, one cone portion having a pair of lateral holding ears and the other cone portion having a corresponding pair of surface recesses separated from the bore of the expansion sleeve by bottom webs and adapted for engagement with said holding ears.

7. In an expansion bolt, an expansion sleeve formed with a screw-thread in the rear portion of its central bore and divided longitudinally to form a pair of substantially counterpart sleeve sections provided 115 on their exterior with teeth or serrations which have a semi-circular form at their bases and a semi-elliptical form at their crowns, the said sleeve sections having at 120 their forward ends terminal cone portions, and means adjacent to said cone portions for securing the sleeve sections together.

8. In an expansion bolt, an expansion sleeve formed with a screw-thread in the 125 rear portion of its central bore and divided longitudinally to form a pair of substantially counterpart sleeve sections provided on their exterior with teeth or serrations which have a semi-circular form at the 130

bases and a semi-elliptical form at their crowns, the said sleeve sections having at their forward ends terminal cone portions having diametrically disposed fins on their exteriors, and means adjacent to said cone portions for securing the sleeve sections together.

Signed at Chicago, Illinois, this 10th day of June, 1914.

ARTHUR C. BARRETT.
